CLAIM

The ornamental design for a “packaging,” as shown and described.

DESCRIPTION

FIG. 1 is a top plan view of the packaging showing our new design, in unfolded condition, including blisters for holding pharmaceutical products;

FIG. 2 is a bottom plan view thereof;

FIG. 3 is a front elevational view of the packaging of FIG. 1, the rear elevational view being a mirror image thereof; and,

FIG. 4 is an end elevational view of the packaging of FIG. 1 illustrating the three rows of blisters thereof.

1 Claim, 1 Drawing Sheet

FIG. 1

FIG. 4

FIG. 2

FIG. 3
